IRONING BOARD

Jesse W. Richardson, Cincinnati, Ohio, assignor
to The Rich Pump & Ladder Company, Cincinnati, Ohio, a corporation of Ohio

Application August 26, 1932, Serial No. 630,561

7 Claims. (Cl. 68—10)

This invention relates to improvements in an ironing board of the collapsible type.

An object of the invention is to provide a novel construction of means whereby the supporting structure for the ironing board is rendered exceedingly compact when the device is collapsed, and wherein the legs of the device are automatically spread apart, by the use of simple means, when the device is set up for use.

10 A further object is to simplify structures of the character above referred to, and to reduce the cost of manufacture by means of a saving in labor and material.

15 The foregoing and other objects are attained by the means described herein and disclosed in the accompanying drawings, in which:

Fig. 1 is a perspective view of the improved ironing board.

Fig. 2 is a bottom view of the device in a collapsed condition.

Fig. 3 is a perspective view of one of a pair of leg spreaders forming a part of the invention.

As is most clearly illustrated in Fig. 1, the device of the invention comprises a table or slab 4 which has mounted adjacent to its rear end 5 a pair of bracket members 6 which extend substantially perpendicularly from the under surface of the table. Each bracket has pivotally mounted thereon as at 7, a table supporting leg 8 which, for convenience in description, may be referred to as the pair of rear legs. These legs are adapted to be moved about the pivots 7 for assuming either the extended position shown in Fig. 1, or the collapsed position indicated in Fig. 2. At 30 points such as 9 intermediate the opposite ends of the supporting legs, are pivoted the rear leg braces 10 and 12, each of which extends forwardly from the pivotal points 9. It will be noted that said braces converge toward the front end 13 of the table or slab member 4.

In the region of the forward end of the table is mounted a U-shaped member 14, the legs 15 and 16 of which have outwardly turned ends 17 adapted for reception in spaced brackets 18 which are screwed or otherwise fixedly secured to the under face of the table. The brackets 18 provide pivotal mountings whereby the U-shaped member may be moved, by means of a handle 19, in a longitudinal plane which is perpendicular to the plane of the table. At the locations 20 and 21, the intermediate portion 22 of the U-shaped member is mounted pivotally upon the rear leg braces 10 and 12, respectively, near the forward ends thereof. Thus, it will be observed that 50 when the handle 19 is grasped for moving the

U-shaped member downwardly and forwardly about the pivots 17, the rear leg braces 10 and 12 will move forwardly and carry with them the rear legs 8 to which said braces are pivotally connected. The legs and braces thereby are moved to the collapsed condition indicated in Fig. 2, and the legs, braces, and U-shaped member 14 are caused to lie closely against the under surface of the table portion. Attention is directed to the fact that the U-shaped member 14 10 preferably has a snap movement caused by its passing from dead center while being moved to the operative position of Fig. 1. Said snap movement is effected by means of the stabilizing rods 23 and 24 which are pivotally mounted upon the front leg 25 of the device, at a point 26 which may conveniently be located near the free end of the front or third leg. Said third leg 25 has a pivotal mounting 27 upon a bracket 28 which is screwed, riveted, or otherwise secured to the under surface of the table. The pivoted end of leg 25 preferably is cut with a taper, as at 29, so that it may have a secure and substantial abutment upon the table. It is to be noted further that the pivot 27 is removed some little 15 distance from the upper end of the leg, so that downward and rearward movement of the end 26 may be effectively arrested by the lever action between the points 27 and 29. The stabilizing rods have their rearmost ends provided with a 20 suitable knob or the like, 30, which abuts a part 31 in the region of the rear legs, and thereby limits forward and upward movement of the front leg. 25

Attention is directed now to a form of means 30 whereby the rear legs 8 are spread apart automatically as they are moved to the extended or operative position shown in Fig. 1. Said means comprises a pair of crossed leg spreader members 32 and 33 which are attached in a peculiar manner, to the legs 8 and to the rear leg braces 10 and 12. The upper ends of the leg spreaders are pivoted to the legs at points 34 and 35, which points may be at or below the pivotal mountings 7. Each leg spreader member has the lower end 35 formed in accordance with the disclosure of Fig. 3. The lower end of each leg spreader preferably is turned rearwardly, as at 36, at substantially right angles to the plane thereof, and in the region of the turn or bend each has formed 40 therein an elongated slot 37 which is included in the bend. Each of the slots is adapted for 45 reception of a stabilizing rod, the heads 30 of which are adapted to abut the concave areas 50 38 of the ends 31. 55

A perforated lug 38 extends from each leg spreader member in substantial perpendicularity thereto, and provides a means whereby the leg spreaders may be pivotally mounted upon the inner faces of the rear leg braces, as indicated at 40 and 41. It will be observed that the pivot 40 is spaced from the adjacent pivot 8. Said pivot 40 may be referred to as a shiftable pivotal mounting for the lower end of the leg spreader, 10 because the effect of moving the brace 12 upwardly about its pivot 8, is to move upwardly also the pivotal mounting 40, to a position closer to the pivot 38; and likewise, the shiftable pivot 41 is moved upwardly closer to the pivot 34 when the brace 10 is moved upwardly about 15 its pivot 8. Since the pivots 34 and 35 are fixed relative to the legs of the device, the spreader members therefore are subjected to a longitudinal compressive strain; and inasmuch as the 20 spreader members are stiff enough to resist bending, the legs 8 must move outwardly due to the compressive strain imposed upon the spreader members by the upward movement of the shiftable pivots 40 and 41.

From the foregoing, it should readily be understood that by grasping the handle 18 (Fig. 1) and moving it forwardly through an arc toward the table end 13, the shiftable pivotal connections 40 and 41 will move in a direction away from the 25 pivots 34 and 35, whereby to pull the legs 8 toward one another, until finally they assume the substantially parallel relationship indicated in Fig. 2; and conversely, when the handle member 18 is moved from the position of Fig. 2 rearwardly through an arc determined by the length of the arms 15 and 16, the distance decreases 30 between the uppermost leg spreader pivots and the shiftable pivots 40 and 41, thereby setting up in the leg spreaders the longitudinally compressive force which is translated into outward 35 movement of the legs as explained above.

The length of the stabilizing rods 23 and 24 is such that the knobs 38 thereof, upon rearward projection of the legs 8 by the action of handle 18, will contact the abutments 39 shortly before the members 10 and 14 attain a dead-center alignment, so that the handle 18 assumes its final position, (as shown in Fig. 1), with a snap action. Thus the various parts of the structure 40 are maintained under a limited strain when the device is in use, so as to insure a degree of rigidity precluding wobbling of the structure.

When the device is collapsed, all parts of the supporting structure are disposed within the limits of the side edges of the table, thereby facilitating storage and carrying of the device from place to place. The various parts lie so flat upon the table, when the device is collapsed, that it can be stored in a container approximately three 50 inches in depth, and this advantage is one of considerable merit.

What is claimed is:

1. In a folding ironing table, a board, a pair of legs mounted on said board for swinging together and apart and toward and from the board, a pair of braces pivotally mounted at one of their ends intermediate the ends of said legs, a pair of links pivotally mounted intermediate the ends of said braces and on the bottom of said board 55 so that the legs are limited to substantially the vertical position, or to a position flat against the bottom of said board, and a pair of cross braces pivotally mounted at one of their ends upon said legs and at their other ends upon said first braces at points intermediate the pivot 60

points of the first braces with the legs and with said links.

2. In a device of the class described the combination of a table, a pair of legs mounted on the under face of said board for swinging toward and from said board to collapsed and extended positions, a third leg mounted on the under face of said board for swinging toward and from said board to collapsed and extended positions, the pair of legs and the third leg extending toward 10 the same end of the table when in collapsed positions, a pair of braces one each having an end pivoted to one each of said pair of legs, and each having a top face opposed to the under face of the table, a mounting including a cross piece, 15 the mounting having ends pivotally mounted on the under face of the table and having the opposite ends of the cross piece thereof pivotally attached to the braces close to the top faces thereof whereby to provide a space between the 20 braces and below said cross piece, means for bracing and connecting the legs, the said third leg having its connection with the board disposed intermediate said cross piece and the 25 mountings of the pair of legs on the board whereby in the collapsed positions of the legs, the said third leg is received in the above mentioned space and all of the legs are disposed in substantial 30 parallelism with and immediately adjacent the under face of the board.

3. In a device of the class described the combination of a table, a pair of legs mounted on the under face of said board for swinging toward and from said board to collapsed and extended positions, a third leg mounted on the under face 35 of said board for swinging toward and from said board to collapsed and extended positions, the pair of legs and the third leg extending toward the same end of the table when in collapsed positions, a pair of braces one each having an end pivoted to one each of said pair of legs, and each having a top face opposed to the under face of the table, a mounting including a cross piece, the mounting having ends pivotally mounted on the under face of the table and having the opposite 40 ends of the cross piece thereof pivotally attached to the braces close to the top faces thereof whereby to provide a space between the braces and below said cross piece, the said third leg having its connection with the board disposed intermediate said cross piece and the mountings of the pair of legs on the board whereby in the collapsed 45 positions of the legs, the said third leg is received in the above mentioned space and all of the legs are disposed in substantial parallelism 50 with and immediately adjacent the under face of the board, cross braces for the pair of legs having mountings for moving the free ends of said pair of legs laterally and outwardly as the said legs are moved from collapsed to extended 55 positions, a connecting rod limiting the extent to which the free end of the third leg may be spaced from the free ends of said pair of legs, said rod, legs, braces, mounting for the braces, and cross braces, when moved to the positions 60 they assume incident to full extension of the legs providing a straining, buckling or snap effect whereby the ends of the braces adjacent the said mounting for the braces are urged against the under face of the board.

4. A device of the class described comprising a table, a pair of legs pivoted to the rear end of said table for pivotal movement toward and from the table, a toggle device comprising a pair of braces pivotally connected to said legs and 70

- a U-shape member having its arms pivotally connected to the table and having the base thereof extending between and connecting the forward ends of the braces, a third leg pivoted to the 5 table intermediate the connections of said pair of legs and the U-shape member to the table, said third leg being movable toward and from the table about its said pivoted connection to the table and the free end of said third leg extending 10 in the direction of the pair of legs when moved toward the table, cross braces for the pair of legs and having their upper and lower ends mounted, respectively, on the legs and braces, a connection for limiting the relative movement 15 of the third leg and the pair of legs as they are moved from the table and incident to which movement the pivoted end of the third leg is brought into contact with the under face of the table and a condition of strain or tension is created, 20 said legs and U-shape member being pivotally connected to the table at such points and the braces being of such length and being attached to the pair of legs at such points that when the legs are turned down from the table, 25 the toggle device will snap over the dead center line between the mountings of the braces on the legs and of the U-shape member on the table and the forward ends of the braces will be urged against the under face of the table.
- 30 5. In a folding ironing table, a board, a rear leg structure comprising a pair of legs each having an end mounted on said board at the rear end thereof, for swinging of the free ends of the legs together and apart and toward and from the board, a pair of braces one brace having an 35 end mounted pivotally on one leg intermediate the ends of the leg and the other brace having an end mounted pivotally on the other leg the braces being so connected near their other ends that they will move together, means on the under face of the board for retaining the braces in an extended position wherein the legs are projected to substantially their fullest extent from one another and from the board, a third leg pivoted at 40 its one end on the board and movable to a folded position in which it extends substantially parallel with the board and to an extended position 45 in which the free end thereof projects forwardly
- and away from the board, a pair of cross braces pivotally mounted at one of their ends upon said legs of the rear leg structure and at their other ends upon said first braces at points intermediate the connected ends of the first mentioned braces and the pivotal mountings of the braces on the legs, and means for connecting the free end of the third leg with the rear leg structure for limiting the movement of the pair of legs beyond a substantially vertical position and whereby the 5 said first pair of braces is rigidly positioned between the rear legs and the brace retaining means on the under face of the board.
6. In a collapsible structure the combination 15 of a table, a pair of supporting legs movable to extended and collapsed positions and having a pivotal mounting upon the table, a pair of crossed leg spreader members one of which has an end thereof pivoted upon one supporting leg, and the other of which has a corresponding end thereof pivoted upon the other supporting leg, a pair of braces each of which has an end pivoted upon a leg, a shiftable pivot on each brace near said pivoted end, to which pivots are attached the opposite corresponding ends of the crossed leg 20 spreader members, and means for holding the braces in rigid relationship with the table upon completion of the movement of the legs to the 25 extended position.
7. In a collapsible structure the combination 30 of a table, a pair of supporting legs movable to extended and collapsed positions and having a pivotal mounting upon the table, a pair of crossed leg spreader members one of which has an end thereof pivoted upon one supporting leg, and the other of which has a corresponding end thereof pivoted upon the other supporting leg, a pair of braces each of which has an end pivoted upon a leg, a shiftable pivot on each brace near said pivoted end, to which pivots are attached the opposite corresponding ends of the crossed leg 35 spreader members, and means for guiding the braces as the supporting legs are moved from the collapsed position to the extended position, including a toggle for maintaining 40 the shiftable pivots in the shifted positions.

JESSE W. RICHARDSON.
